UNITED STATES PATENT OFFICE

JOHN RITCHIE, OF NEW DEER, ABERDEEN, SCOTLAND

MOVING TARGET

Application filed May 5, 1930, Serial No. 449,916, and in Great Britain May 6, 1929.

This invention relates to moving clay targets used chiefly for giving instruction in the use of gun or rifle. These are made of clay and sand, plaster or other frangible material in the form of rabbits, game birds or the like which on being hit are broken into fragments and completely disappear.

An important object of the invention is to provide apparatus wherein any required number of targets may be carried on a moving endless band (including a chain, cord, belt or equivalent) in clips so constructed that upon a target being broken (and only its stub being left in the clip) a new target can be simply held in the path of the advancing clip and will eject the old stub and itself be carried forward in the clip.

Other objects and advantages of the invention will be understood from the description 20 of an embodiment thereof which follows and from the claims.

Referring to the accompanying drawings,

Figure 1 illustrates the front view of moving targets arranged in a landscape.

Figure 2 shows to an enlarged scale the clip whereby the targets are secured to the endless band.

Figure 3 shows the clips secured to a chain.

Figure 4 shows the clips secured to a flat belt.

Figure 5 shows a target to a slightly larger scale.

The targets 1 made of frangible material are each formed with a projection 2 for engagement by a spring clip 3. The clip has a flared front opening 4, a main portion comprising bottom 5 and sides 6, and a backward extension 7 of one of the sides. The sides may have upper flanges 8 helping to set the level of the target and one or more holes in the bottom 5 may be used for securing the clip to the endless band 9. The backward extension 7 has a vertical inward projection 7a formed upon it a little way back from the back of the body.

The band 9, comprising for example a chain driven by a sprocket 10 as shown at Figure 3, or a belt driven by a pulley 10a as shown at Figure 4, passes in front of a screen 11 behind which a man may stand in safety.

The clips on the chain or belt can thus be charged with fresh targets while in motion.

The chain or belt itself may be masked in front by a screen 12 above which the targets project. The screen may be made shot or bullet-proof to protect the chain, belt or like and the carrier.

In operation an attendant can stay behind the screen where the return run of the belt is exposed. If a target has been struck the attendant simply holds another in the line of advance of the clip. The flared front opening and upper flanges help to guide its projection 2 into the main body of the clip simultaneously ejecting the stub of the old target: 65 immediately the latter leaves the main body it drops away and the backward extension springs inwardly again enough to bring the projection 7a into the path of the new target. Thereupon the operator releases the latter 70 which is sufficiently firmly held by the clip. With a little practice, an operator can thus replace targets while the band is moving at the full speed desired.

I claim:—

1. Apparatus of the kind described comprising an endless band, a number of clips thereon, frangible targets, for insertion in said clips, the said clips comprising a body portion and a catch portion, the insertion of a new target automatically pushing the stub of a broken target out of the body portion and the catch returning to check and locate the new target in correct position.

2. Apparatus of the kind described comprising an endless band, a number of clips thereon, frangible targets for insertion in said clips, the said clips each comprising a flared front opening, a body portion, and a spring catch spaced backwardly from the body portion for the purpose described.

3. Apparatus of the kind described comprising an endless band, a number of clips thereon, frangible targets for insertion in said clips, the said clips each comprising a piece of sheet metal bent to form a flared front opening, the bottom and sides of a body portion and a backward extension of one of said sides the said backward extension including an inward vertical indentation.

4. Apparatus of the kind described comprising an endless band, a number of clips thereon, frangible targets for insertion in said clips, the said clips each comprising a piece of sheet metal bent to form a flared front opening, the bottom and sides of a body portion, flanges at the top of said sides, and a backward extension of one of said sides the said backward extension including an inward vertical indentation.

10 In testimony whereof I affix my signature.
JOHN RITCHIE.
